Primary Examiner — Eliza Z Harvey*Assistant Examiner* — Kayla Marie Bennett(74) *Attorney, Agent, or Firm* — Piloff Passino & Cosenza LLP; Martin J. Cosenza(57) **CLAIM**

The ornamental design for a bow shackle assembly, as shown and described.

DESCRIPTION

FIG. 1 is a perspective view of the bow shackle assembly shown in a closed configuration of use;
FIG. 2 is a front view of the bow shackle assembly shown in a closed configuration of use;
FIG. 3 is a right side view of the bow shackle assembly shown in a closed configuration of use;
FIG. 4 is a top view of the bow shackle assembly shown in a closed configuration of use;
FIG. 5 is a cross-sectional front view of the bow shackle assembly shown in a closed configuration of use, which cross-section is along the line of 5-5 of FIG. 4;
FIG. 6 is a cross-sectional perspective view of the bow shackle assembly shown in a closed configuration of use, which cross-section is along the line of 6-6 of FIG. 1;
FIG. 7 is a perspective view of the bow shackle assembly shown in an open configuration of use;
FIG. 8 is a front view of the bow shackle assembly shown in an open configuration of use;
FIG. 9 is right side view of the bow shackle assembly shown in an open configuration of use;
FIG. 10 is a top view of the pin of the bow shackle assembly;
FIG. 11 is a perspective view of the pin of the bow shackle assembly;
FIG. 12 is a front view of the pin of the bow shackle assembly;
FIG. 13 is a top view of the pin of the bow shackle assembly shown in an open configuration of use;

(Continued)

FIG. 14 is a cross-sectional front view of the bow shackle assembly shown in an open configuration of use, which cross-section is along the line of 14-14 of FIG. 13; and, FIG. 15 is a cross-sectional perspective view of the bow shackle assembly shown in an open configuration of use, which cross-section is along the line of 15-15 of FIG. 7. The front views are shown in FIGS. 2, 8 and 12. The back views of these figures which are not shown in the drawings are mirror images of the front views.
